(57) **CLAIM**

The ornamental design for a mountable information handling system as shown and described.

DESCRIPTION

FIG. 1 is a front, top and left side perspective view a mountable information handling system, showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom, rear and right side perspective view thereof;

FIG. 9 is a front, top and left side perspective view thereof, shown in an environment of use; and,

FIG. 10 is another front, top and left side perspective view thereof, shown in an environment of use.

Broken lines shown in FIGS. 1-8 illustrate portions of the mountable information handling system that form no part of the claimed design. The broken lines illustrating the desk, cords, monitor, keyboard and mouse in FIGS. 9 and 10 are environment, while the remaining broken lines in FIGS. 9 and 10 illustrate portions of the mountable information handling system that form no part of the claimed design.

1 Claim, 7 Drawing Sheets
